UNITED STATES PATENT OFFICE.

GARRETT E. CARHART AND CONRAD K. HOTALING, OF WASHINGTON, D. C.

DESIGN FOR FRONT OF A PARLOR-ORGAN CASE.

Specification forming part of Design No. 7,873, dated November 24, 1874; application filed November 9, 1874.
[Term of Patent 3½ years.]

To all whom it may concern:

Be it known that we, GARRETT E. CARHART and CONRAD K. HOTALING, of Washington, in the county of Washington and District of Columbia, have invented a new and original Design; and we do hereby declare that the following is a full, clear, and exact description of the nature of the same, reference being had to the annexed drawings, making a part of this specification, and to the letters and figures of reference marked thereon.

Figure 1 of the drawings is a representation of the perspective elevation of my design, showing the upright case of a parlor-organ, melodeon, or an upright piano, having within its beaded or scrolled edge the shaped or beaded panel-work, as shown.

Our invention is a new design for the front of the case of a parlor-organ, upright piano, or similar musical instrument; and consists essentially of a scrolled front to the upright case of a musical instrument, as aforesaid, said front being provided with ornamental panels, as hereinafter described.

The letter A represents the body-case of a parlor-organ, and B the said scrolled front. This front is beaded along its scrolled edges, and has formed upon its surface ornamental panels a, as shown. The said panels, within their ornamental edges or moldings, may be temporarily covered with mirrors, paintings, prints, &c., as may be desired; therefore,

What we claim as our invention, and desire to secure by Letters Patent, is—

A design for the case-front of a parlor-organ or upright piano, substantially as shown and described.

In testimony that we claim the above we have hereunto subscribed our names in the presence of two witnesses.

GARRETT E. CARHART.

CONRAD K. HOTALING.
